GENERAL MOTORS CORPORATION, OF DETROIT, MICHIGAN, A CORPORATION OF
DELAWARE

BODY STRIPING TOOL

Application filed August 8, 1927. Serial No. 211,497.

This invention relates to apparatus particularly designed for applying ornamental stripes to motor vehicle bodies.

At the present time, striping is done by skilled painters equipped with brushes having bristles narrowed down to a thin edge. In view of the skill required, competent painters are hard to obtain and the expense of striping is great.

10 In the present application, there is disclosed a striping tool which can be successfully employed by unskilled labor. The tool is designed so that it may be used either to produce one stripe or a row of parallel stripes. 15 It consists essentially of a feeding device for contacting with the work and applying the stripe, the feeding device being supplied with paint or other striping material from a suitable reservoir. The tool is provided with a 20 shut-off valve, preferably operated by a plunger extending to the point of the feeding device, for cutting off the flow from the reservoir when the device is removed from the work.

25 We have found it desirable to provide an agitator for mixing the paint in the reservoir during the striping operation so as to insure that it will be in proper condition to flow freely on to the work. The agitator may consist of a simple paddle wheel mounted on a shaft driven by an air or electric motor. In case an air motor is employed, we may conduct the exhaust to a point where it may blow upon the stripes already applied and dry them.

30 35 In some cases, particularly where several stripes are applied at one time, it may be desirable to mount the feeding devices so that they will be yieldingly held against the body, thus insuring that each feeding point will be at all times in contact with the work, whatever the curvature of the surface to be striped.

In the drawings:

Figure 1 is a side elevation partly in section showing the tool in position to apply stripes to the beading on an automobile body.

Figure 2 is a section on line 2—2 of Figure 1.

Figure 3 is a section on line 3—3 of Figure 1.

Figure 4 is a section on line 4—4 of Figure 1.

Figure 5 is a view similar to Figure 1 but with all parts in elevation.

Figure 6 is a top plan view of the construction of Figure 5. 55

Figure 7 is a view corresponding to Figure 5 but showing a simplified construction.

Figures 8 and 9 are details of modified arrangements for spring mounting the feeding pens. 60

Figures 10 and 11 are sectional views showing modified forms of feeding devices.

Our striper consists of a U-shaped frame 10 in the ends of which is journalled a shaft 12. 65 At one end of the shaft is keyed the rotor 16 of an air motor. The rotor is enclosed in housing 18 supplied with compressed air through tangentially arranged conduit 20. Air leaves the casing 18 through exhaust pipe 22 and is preferably conducted to a point adjacent the body where it exerts a drying action on the stripes previously applied. This will be later described. 70

Upon the shaft 12 are likewise mounted reservoirs 24, each of which is provided with a suitable port 26 for the introduction of paint, Duco, or other striping fluid. The reservoirs are provided with vents 30 equipped with ball valves 32 for the admission of air to replace the fluid fed to the tool. 75 As it is essential that the fluid be agitated to prevent separation of the pigment and vehicle, we have mounted on the shaft 12 within each of the housings 24 an agitator 34 in the form of a paddle wheel. This is particularly desirable in the case of gold striping because with this fluid, the pigment will invariably separate out if the fluid is not mixed and remixed with great frequency. The manner of feeding the striping fluid from the reservoir to the work is the same in each case so that but one of the devices will be described. 85

Leading from each of the reservoirs 24 is 85 a tube 36 which may be provided with one or more bores 38 leading to feeding devices 40 for engagement with the work. The feeding devices are very similar to the drawing pens commonly used by draftsmen. Each 100

consists of a central strip 42 of steel or other flexible material and side strips 44 on either side of the central strip. The central strip is provided with opposite bosses 46 from which 5 project threaded studs 48 extending through perforations in the side strips and equipped with nuts 50. The strips converge toward their ends and by adjusting the nuts 50 the gaps between the ends of the strips may be 10 regulated. Obviously, with the construction so far described, striping fluid would flow from the reservoir to the space between the strips and thence pass by capillary action to the point of the feeding device and thence on 15 to the work.

While we have shown a considerable gap between the ends of the bores 38 and the point of the feeding device, it is obvious that this may be reduced or increased as found most 20 desirable.

In order to prevent the loss of striping fluid when the tool is removed from the work, we have provided valves in the form of spring-pressed balls 52 shown as located adjacent 25 to the point of connection of the reservoirs with the tubes 36. The ball engage seats formed at the inner ends of the bores 38. Each ball is mounted on a wire 54 extending through the passage 38, through guide aperture 56 30 formed in bosses 46, the wire terminating at the point of the feeding device in ball member 58. Normally, the springs 53 cause the members 58 to project beyond the tips of the strips 44 so that upon beginning the striping 35 operation, the members 58 are depressed, the balls 52 unseated and striping fluid is supplied to the feeding device.

It should be noted that the rotation of the agitator creates a slight pressure in the reservoir 40 so that there is a forced flow of fluid to the feeding device when the balls are unseated. The amount of this pressure may be regulated by varying the speed of the air motor. The members 58 serve to assist in 45 spreading the striping material on the work and may be given any desired shape to facilitate this action.

While we have shown each feeding device to be composed of three strips it is obvious that 50 a greater or less number may be employed if a wider or narrower stripe is desired.

In Figure 10 we have shown a modification of the feeding device in which four strips of steel are employed. Here reference character 55 42' indicates the central strip, while the side strips are indicated by the reference characters 44'. The construction is otherwise the same as that shown in Figure 1.

In Figure 11 we have shown a modification 60 of the feeding device in which but a pair of steel strips 47 are made use of. This construction is likewise the same in other respects as that illustrated in Figure 1.

Figures 1 and 5 show the manner of using 65 the device. 60 indicates a portion of the

metal bead now commonly used on automobile bodies and to which it is desired to apply the stripes. Adjacent the body may be mounted a pair of tracks 62 on which the apparatus is supported by means of rollers 70 75 clamped to the tubes 36. The clamp carrying the outer roller 64 may, as shown in the drawings, engage three of the tubes 36 so as to hold them properly spaced. Obviously, by the substitution of clamps having different spacing or by employing adjustable clamps, the feeding devices may be located at different distances apart, the tubes 36 yielding sufficiently for the slight variations necessary. The operator rests the striping 80 on the rails 62 in the manner shown and after having first adjusted the strips 42-44 so as to obtain the proper width of stripe, starts the air motor thereby driving the agitators 34, and presses the feeding points against the body. This 85 action results in unseating the valves 52 and striping fluid is supplied to the points. The striping 90 is then drawn along the body and the stripes are applied.

As shown in Figures 5 and 6, the exhaust 90 pipe 22 of the pump may be led to nozzle 68 supported from the fixture in position so that a blast of air is directed on the freshly applied stripes so that the latter are thereby 95 quickly dried.

Our apparatus is capable of considerable modification; thus, in the simplified form shown in Figure 7, but one feeding device 36 is employed. To insure even feed of striping 100 fluid to the points, these may be spring urged 105 against the work by utilizing the modifications shown in either Figures 8 or 9. Thus, in Figure 8, the tube 36 is provided with an outwardly turned flange 70 and within the tube is telescoped a short pipe 74 mounted in the 110 reservoir. A spring 76 is interposed between the flange 70 and the body of the reservoir to yieldingly urge the feeding device outwardly. A pin and slot connection, such as shown at 78 may be employed to limit the 115 outward movement of the tube 36.

In the construction shown in Figure 9, the outer strips 40-44 are mounted on a sleeve 80 encircling the tube 36 and yieldingly urged 115 outwardly by means of coil spring 82. Stops 84 may be provided to permit disengagement of the strips from the tube.

While we have shown the tool as supported in use upon rails 62, it is obvious that various other types of guiding means may be employed or these may be dispensed with altogether.

Various other changes in construction will suggest themselves to those skilled in body work.

We claim:

1. The combination of a plurality of fluid feeding devices, means for supplying said devices with fluid, and a yieldable connection interposed in each of said devices for permit- 130

- ting them to adjust themselves to irregularities in the surface of the work.
2. In a striping fixture, the combination of a fluid reservoir, a fluid feeding device connected with the reservoir, an agitator for the reservoir, a compressed air motor for driving the agitator, and means for conducting the exhaust from said motor to the vicinity of the feeding device to effect drying of the material applied.
3. In striping apparatus the combination of a fluid reservoir, a fluid feeding device communicating with the reservoir for applying the fluid, a rotary agitator comprising a blade in the reservoir, said agitator closely fitting the periphery of the reservoir but being spaced from the other walls of the reservoir to permit fluid to pass from one side to the other of the agitator blade, said reservoir being provided in its periphery and adjacent the path of movement of said agitator with a port adapted to conduct fluid to said feeding device, and means for driving said agitator.
4. A hand striping tool comprising a reservoir, a fluid feeding conduit mounted on the reservoir, fluid flow controlling means for the conduit, said conduit comprising yieldable telescopic sections to permit the feeding device to follow the irregularities in the work.
5. In a striping tool the combination of a frame, a shaft journaled in the frame, means for driving the shaft, reservoirs carried by the shaft, means for keying the reservoirs against rotation with the shaft, fluid impelling means mounted on the shaft and housed within the reservoirs, and fluid feeding devices leading from the reservoirs, and provided with means for controlling the flow of fluid therethrough.
6. In a hand striping tool the combination of a U shaped frame, a shaft carried in the frame and bridging the U, a reservoir mounted on the shaft, means for locking the reservoir to the frame, a conduit leading from the reservoir and provided with fluid feeding means, and means for controlling the flow of fluid through the conduit.
7. In a portable hand-operated striping device for automobile bodies, in combination, a pair of applicators for forming two spaced parallel stripes in the same plane, a third applicator for forming in the same plane an intermediate stripe contiguous with said parallel stripes, and means for conducting the striping fluid to said applicators.
8. In a striping device for automobile bodies, means for producing a stripe as the device is moved over the body, means for producing in the same plane a margin for said stripe, and means for guiding both of said means.
9. In a striping device for automobile bodies, an applicator for producing a stripe as the device is moved over the body, and means for producing in the same plane a margin for said stripe along each edge thereof.
10. In a striping device for automobile bodies, in combination, a pair of applicators for forming two spaced parallel stripes in a single plane, a third applicator for simultaneously forming an intermediate stripe touching said parallel stripes, and means for conducting striping fluid to said applicators.
- In testimony whereof we affix our signatures.
